BOTTLE OPENER

Samuel J. Kaufman, New York, N. Y.

Application March 29, 1954, Serial No. 29,749

Term of patent 7 years

(Cl. D44—29)

To all whom it may concern:

Be it known that I, Samuel J. Kaufman, a citizen of the United States, residing at New York city, in the county and State of New York, have invented a new, original, and ornamental Design for a Bottle Opener, of which the following is a specification, reference being had to the accompanying drawing, forming a part thereof.

Fig. 1 is a front elevational view of a bottle opener, showing my new design.

Fig. 2 is a side elevational view thereof.

Fig. 3 is a rear view thereof.

Fig. 4 is a top plan view thereof.

I claim:

The ornamental design for a bottle opener, substantially as shown.
